UNITED STATES PATENT OFFICE.

FRANK THEODORE SWEIGART, OF KOKOMO, INDIANA.

GAS-ENGINE STARTER.

969,756.

Specification of Letters Patent. Patented Sept. 6, 1910.

Application filed January 29, 1909. Serial No. 475,014.

To all whom it may concern:

Be it known that I, FRANK THEODORE SWEIGART, a citizen of the United States, residing at Kokomo, in the county of Howard and State of Indiana, have invented certain new and useful Improvements in Gas-Engine Starters, of which the following is a specification.

The object of my invention is to produce a mechanism by means of which an internal combustion engine may be started without manual operation, as is now customary.

The accompanying drawings illustrate my invention.

15 Figure 1 is a diagrammatic view showing the application of my apparatus to the engine of an automobile; Fig. 2 a front elevation of the parts shown in Fig. 1; Fig. 3 a detail, on a larger scale, of the starting motor, the front plate being removed; Fig. 4 a section on line 4—4 of Fig. 3; Fig. 5 a section on line 5—5 of Fig. 3, and Fig. 6 a detail of the ratchet connection between the starter and the engine shaft.

25 In the drawings, 10 indicates a cylinder of a gas engine which, in the drawings, is shown as an automobile engine mounted upon suitable frame 11. Leading from cylinder 10 is a pipe 12 in which is mounted a check valve 13 opening outwardly from the cylinder. Pipe 12 leads into a storage tank 14 and leading from said storage tank is a pipe 15 in which is mounted a controlling valve 16, a suitable operating member therefor being carried to any desired point convenient of access by the chauffeur. Pipe 15 delivers to a pair of admission chambers 17 of the starting motor 18 which comprises a shaft 19. Shaft 19 carries, at its rear end, 30 a ratchet wheel 20, and secured to the shaft 21 of the engine is a head 22 carrying pawls 23 adapted to coöperate with the ratchet 20. Any suitable form of motor may be used to drive shaft 19 but I prefer a small motor of

45 the steam engine type. Said motor comprises a pair of oscillating cylinders 25 provided at opposite ends with ports 26 and 27 which open through surfaces coöperating with a port plate 28. Port plate 28 is provided with a pair of separated ports 29 and 30 at each end the ports 29 communicating with the admission chamber 17 and the ports 30 communicating with the atmosphere so that, in the usual and well known manner 50 an oscillation of the cylinder 25 upon its trunnions 32 will bring ports 26 and 27 al-

ternately into register with the ports 29 and 30. The port face of each cylinder is held against the port plate by a suitable spring 33. Mounted within each cylinder is a piston 34 connected by a piston rod 35 with a wrist pin 36 carried by a gear 37 journaled within the casing 18 and meshing with a gear 38 secured to shaft 19. In order that the gear 37 may have a long bearing, I provide an extension sleeve 41 on the back of the casing 18 as clearly shown in Fig. 4.

While the apparatus thus described is intended to obviate any necessity for manually starting the motor, it is desirable of course 40 to make arrangements by means of which the motor may be started manually in case of accident to the starting motor and I therefore project shaft 19 out of the forward plate of casing 18 and form the exposed end 19' 5 to receive an ordinary starting lever. This exposed end can be conveniently covered by means of a screw cap 42.

In operation, the first time the engine is put into service, it must be manually started 80 and the first few explosions in cylinder 10 cause portions of the exploded charge to pass beyond check valve 13 and through pipe 12 into reservoir 14 where the pressure is retained by the check valve 13 and controlling valve 16. During this operation the shaft 21 rotates freely relative to shaft 19. After the motor has been stopped, it may be readily started by opening valve 16, 85 permitting pressure from the reservoir 14 to pass to the cylinders 25 and actuate the pistons therein in the same manner as in a steam engine, this actuation resulting in the rotation of gears 37 and 38 and shaft 19 to rotate shaft 21 in a forward direction and 90 thus start the engine. As soon as the engine is started under its own explosion the pressure within reservoir 14 will be renewed and valve 16 is of course closed.

I claim as my invention:

An automobile starter, comprising a main casing having admission chambers, a pair of oscillating cylinders journaled within the main casing and provided with ports adapted to alternately register with the admission chamber, a pair of pistons one mounted in each of said cylinders, a crank-shaft journaled in said casing and connected with said pistons, a main shaft also journaled in said casing and having its opposite 105 ends projected from opposite sides of the casing, a ratchet connection having one 110

member attached to a projected end of said main shaft and the other member adapted for connection with a shaft of an engine, the opposite end of said main shaft being so formed as to receive a starting crank.

In witness whereof, I, have hereunto set my hand and seal at Kokomo, Indiana this

26th day of January, A. D. one thousand nine hundred and nine.

FRANK THEODORE SWEIGART. [L. S.]
